UNITED STATES PATENT OFFICE

112,846

DESIGN FOR A COMBINED EGG CUP AND COVER THEREFOR

Edward A. Reiser, Dayton, Ohio

Application April 22, 1936, Serial No. 62,238

Term of patent 14 years

To all whom it may concern:

Be it known that I, Edward A. Reiser, a citizen of the United States, residing in the city of Dayton, in the county of Montgomery and State of Ohio, have invented a new, original, and ornamental Design for a Combined Egg Cup and Cover Therefor, of which the following is a specification, reference being had to the accompanying drawing, forming part thereof.

The figure is a perspective view of a combined egg cup and cover therefor, showing my new design.

I claim:

The ornamental design for a combined egg cup and cover therefor, as shown.

EDWARD A. REISER.
